UNITED STATES PATENT OFFICE

157,496

TOY FIGURE

Lloyd D. Hoyt, Northfield, Ill.

Application April 23, 1949, Serial No. 2,217

Term of patent 14 years

(Cl. D34—4)

To all whom it may concern:

Be it known that I, Lloyd D. Hoyt, a citizen of the United States, residing at Northfield, in the county of Cook and State of Illinois, have invented a new, original, and ornamental Design for a Toy Figure, of which the following is a specification, reference being had to the accompanying drawing, forming a part thereof.

In the drawing:

Fig. 1 is a front view of the toy figure, showing my new design;

Fig. 2 is a side view of the same; and

Fig. 3 is a back view of the same.

I claim:

The ornamental design for a toy figure, substantially as shown.

LLOYD D. HOYT.
